UNITED STATES PATENT OFFICE

149,271

DESIGN FOR AN EMBROIDERED TRIMMING

Herman Kaufman, New York, N. Y.

Application April 21, 1947, Serial No. 138,510

Term of patent 7 years

(Cl. D92—1)

To all whom it may concern:

Be it known that I, Herman Kaufman, a citizen of the United States of America, residing in New York city, county of New York, and State of New York, have invented a new, original, and ornamental Design for an Embroidered Trimming, of which the following is a specification, reference being had to the accompanying drawing, forming part thereof, wherein, the figure is a plan view of an embroidered trimming showing my new design.

I claim:

The ornamental design for an embroidered trimming, substantially as shown.

HERMAN KAUFMAN.
